UNITED STATES PATENT OFFICE

WILLIAM HUBERT FITCH, OF FORT WORTH, TEXAS

OPERATING MECHANISM FOR AUTOMATIC TELEPHONES

Application filed February 24, 1930. Serial No. 431,023.

This invention relates to actuating mechanisms for automatic telephones, and has for an object the production of a device adapted to be associated with the impulse controlling organization of any usual and ordinary automatic telephone, of the dial type, and to furnish a manual operating device which shall replace the disk and provide an organization more easily manipulated.

10 A further object of the invention is to provide a slide, carrying the necessary numeration, said slide, in its reciprocation turning the same stud or pintle, to which the dial is ordinarily attached and in the same manner both as to progression and return.

15 A further object of the invention is to provide a structure which will be attached to the base of a telephone, of the usual and ordinary dial type, and replacing the dial, offer means 20 for applying the necessary manual movements to the impulse mechanism, by the mere movement of the finger of the operator in right lines.

25 With these and other objects in view, the invention comprises, the combination of new and novel parts, structures, arrangements, movements and functions, as will be herein-after more fully shown, described and claimed, together with all mechanical and 30 functional equivalents thereof.

In the drawings,

Fig. 1 is a view of the invention in side elevation, attached to a conventional telephone.

35 Fig. 2 is a top plan view, with the top plate removed.

Fig. 3 is a transverse sectional view, taken on line 3—3 of Fig. 2.

40 Like characters of reference indicate corresponding parts throughout the several views.

The invention which forms the subject matter of the present application, is adapted to be attached and applied to any usual and ordinary automatic telephone, of the dial type,

and there has been shown in the drawings, merely by way of illustration, a conventional telephone base A, with housing B, for containing the impulse contact mechanisms of any type, with a stud C, to which in the usual and ordinary practice, the dial is attached.

50 In applying the mechanism of the present invention, the dial is removed or omitted, and in its stead a pinion 10, is employed, which may be secured in any approved manner as 55 by the nut 11. Attached to the housing B is a plate 12, preferably set at an inclination to the plane of the base, and upon this plate a rack bar 13, is mounted to slide, by the employment of any type of guides of other limiting structure. The rack bar 13 carries gear teeth 14, interengaging with the teeth of the pinion 10, so that as the rack bar 13 is manually reciprocated, the pinion 10 and the connected stud C, are moved in a rotary manner, 60 any means being employed, as is customary in the art, to return the parts, when manual stress is released, the spring 15, being shown merely to indicate an operative structure and not as any limitation.

65 To facilitate the correct manipulation of the rack 13, finger receptacles, corresponding to the number of numerical digits, are provided by the abutments 16, the receptacles being properly numerated for convenience.

70 To perform the necessary steps successfully, a stop must be provided for limiting the movement of the rack at each manual movement, corresponding to the amplitude of movement of the stud C to make the necessary 80 impulse contacts. For this purpose a plate 17, is attached to the plate 12, and spaced therefrom in any approved manner, spacers 18, being shown merely as illustrative, and screws 19, similarly shown for rigid attachment. The plate 12, also acts as a guide for maintaining the rack 13 in position.

75 In operation, the finger of the operator is placed against the abutment 16, indicated by the numeral appearing in the number to be 80

called, the finger together with the rack 13 is now moved toward the plate 17, and until the finger makes contact with that plate, whereupon, the finger being removed, the rack is returned to initial position, by the spring 15, or some equivalent recoil mechanism, and the movement repeated for the next and subsequent digits in the number being called.

I claim:

10. 1. The combination with a telephone transmitting organization embodying a rotatable impulse controlling part, a pinion mounted upon the rotatable part, a sliding rack interengaging the pinion, and means to apply manual stress to move the rack.
15. 2. The combination with a telephone transmitting organization embodying a rotatable impulse controlling part, a pinion mounted upon the rotatable part, a rack in engagement with the pinion, means providing a longitudinal sliding movement for the rack, and numerated abutments on said rack for digital engagement.
20. 3. The combination with a telephone organization embodying a rotatable impulse controlling part, a slide adapted to be manually moved and means for converting the sliding movement of the slide into rotary movement of the rotatable part, said slide being provided with a longitudinal series of abutments for digital operation.
25. 4. The combination with a telephone organization embodying a rotatable impulse controlling part, a pinion mounted upon the rotatable part for imparting rotary movement thereto, a slidable rack interengaging said pinion means providing a longitudinal sliding movement for said rack, said rack being provided with abutments arranged in longitudinal series thereon and in staggered relation.
30. 5. A device for attachment to a telephone instrument comprising a rotatable impulse controlling element, a pinion for rotating said element, a slidable rack mounted for engagement with said pinion for rotating the same upon reciprocation of said rack and spring means for returning said parts to initial position.
35. 6. A device for attachment to a telephone instrument comprising a housing containing rotatable impulse controlling means, a pinion mounted on said means, a casing mounted on said housing and enclosing said pinion and provided with guiding means for a slidable rack, a slidable rack mounted in and guided by said casing and in operative engagement with said pinion.

In testimony whereof I affix my signature.

WILLIAM HUBERT FITCH.
